UNITED STATES PATENT OFFICE

OLIVER M. MAISCH, OF CHICAGO, ILLINOIS

CUTTER

Application filed April 20, 1927. Serial No. 185,086.

My invention relates to profile cutters and more particularly provides a tool or cutter for refacing as well as for initially forming valve seats for internal combustion engine valves. The initial design of the internal combustion engine takes into account the size of valve, the angle of taper of the valve face and seat, the width of seat in engagement with the valve face and the spring tension, and all 10 these factors are interrelated to secure the desired action.

In the process of manufacture these factors can be determined and accurately controlled. In use the engine is subject to wear and it is 15 customary to grind the valves into the seats to keep them tight. This grinding increases the width and diameter of the valve seat, but usually to only a very slight extent. However, not infrequently the valve seats become 20 pitted and a tight fit by the usual grinding process is not secured. Then it becomes necessary to reface the valve seat by cutting the same back to solid metal.

The usual service station attendant or repair man has no adequate means for controlling the operation so as to make the refaced valve seat correspond to the original factory made valve seat. Neither has he adequate 25 means for making the valve seats in the same engine alike, whether like the original seats or not.

It is the aim of the present invention to put into the hands of the service station mechanic or repairman a tool by which the valve seat 30 may be refaced and brought to the original dimensions of diameter and width of seat and all valve seats on one engine be made uniform. I am aware that attempts have been made to provide a profile cutter which will do 35 this, but so far as I am able to ascertain no device which can satisfactorily perform this function has been produced.

Obviously, a cutter of the right profile can be produced, but after usage of such a cutter 40 it becomes dulled or worn and must be thrown away, because sharpening changes the size or profile of the cutter. The cutter of my invention is so constructed that by a simple 45 grinding operation it may be dressed or sharpened without changing its size or pro-

file. The key to this lies in the manner of relieving the cutting edges.

In a cutting tool of this character, which is comparable to a compound reamer, the metal behind the cutting edge must be cut back to 55 relieve the cutting edge. In a straight conical reamer the edge may be sharpened by grinding along the front face, i. e., the radial face. This diminishes the diameter of the cutter at any given point, but it does not 60 change the taper of the reamer and, hence, it is merely necessary to advance the reamer to bring into play a portion which has the desired diameter.

I provide in the preferred form of my invention a unitary integral cutter having three cutting faces to define at their intersection 65 two gauge points or circles which are the edges of the desired valve seat. Between these two circles lie the cutters for cutting 70 the actual face of the valve seat and on each side or flank lie the cutters for cutting away the adjacent metal to define the edges of the valve seat. These flank cutters and the valve 75 face cutter are in reality tapered reamers and, according to my invention, all three of these reamers are relieved to the same degree and upon elements of the same family of parallel helices, i. e., upon helices having 80 the same pitch but of various radii.

In the preferred form of my invention each tooth has a radial cutting face and a helical face defining the present and future valve seat cutting edges, and upon one side of said 85 seat cutter there is the flank cutter, and on the other side the port reamer, both being relieved upon the same helical pitch angle.

The key to the present construction therefore resides in the generation of the relief surface on elements or lines which are helices. Now it is to be understood that a radial face is 90 not essential. The cutter might have skewed cutting edges, as for example, helical or spiral, but it is advantageous to have the 95 dressing faces radial to make the matter of sharpening easier and to conform to known practices in tool dressing.

The slight axial shift of the valve seat from the use of my cutter is readily compen- 100

sated for by adjustment of the valve tappet or thrust rods.

There are certain other improvements which my invention provides, such as an improved and interchangeable guide and operating means as will be apparent from the following detailed description of a specific embodiment.

Now to acquaint those skilled in the art with the manner of constructing and practicing my invention, I shall describe in conjunction with the accompanying drawings, a specific embodiment of my invention.

In the drawings:—

Fig. 1 is a side elevational view of my improved cutter and showing it applied to a valve seat;

Fig. 2 is a central longitudinal section through the cutter;

Fig. 3 is an underside view of the cutter, a sharpening wheel being shown applied thereto;

Figs. 4 and 5 are enlarged diagrammatic views showing respectively a valve seat before and after a refacing operation with my improved tool;

Fig. 6 is a diagram explaining the relief, and Fig. 7 is a side view of the lower end of the operating wrench or handle.

The cutter is preferably, but not necessarily, formed from a single piece of suitably hardened steel, and comprises the cylindrical head section 10, which may be termed the flank cutter, the frusto-conical section 11 of less diameter than that of the head, which may be termed the port reamer, and the intermediate valve seat engaging belt or zone

12. The head, skirt and intermediate parts are milled to form the grooves 13 and the cutting tooth segments 14. The milled grooves are shown of triangular cross section, one side of each groove forming the advance or cutting face of a tooth and the other side forming the rear face of the adjacent tooth. In the specific cutter here shown the cutting edge of each tooth lies in a plane passing through the axis of the cutter and the cutting face of each tooth preferably also lies in the same axial plane in which the cutting edge is located. In other words, the advance or cutting face of each tooth in this instance lies in a radial plane so that the cutting edge of the tooth throughout its extent will be in a radial plane at all times.

The teeth are given the necessary relief or drop rearwardly of their cutting edges, and this can be readily accomplished by means of a cam fed tool operating on the rotating cutter in a known form of machine known as a relieving machine. This, however, must be done in a certain manner to secure the full benefits of the present invention.

On most of the automotive vehicle engines the valve seat is at an angle of forty-five degrees with the valve opening axis and in the

valve structure illustrated the seat is about one-sixteenth of an inch in width. When the engine is new, and before the valve seats have been refaced, the upper edges of the seats are coincident with the top surface S of the metal in which the seats are cut, and in the particular structure shown there is a belt or surface T surrounding the valve passage-way below the valve seat and which is at an angle of less than forty-five degrees with the valve axis. This is a common or standard arrangement found in most types of automotive vehicles and the cutter shown has been designed to be used in such types of valve structures. The intermediate zone or belt 12, at the tooth cutting edges, is of the same width as the desired width of valve seat 15 and the cutting edges at the skirt part 11 of the cutter have the same angle relative to the valve axis as the surface T. In the better class of engines the valve ports are machined concentric with the guide for the valve stem and the valve seat 15. This machined surface may be cylindrical or tapered. In either case it provides a suitable guide for the reamer portion 11 to hold the tool in proper axial alignment. The cutting edges of the teeth on the underside of the flange or head part 10 constituting the flank cutter are at an angle with the valve axis of greater than forty-five degrees.

As shown in Fig. 3, the inner and outer edges a and b of the intermediate or valve seat engaging belt 12 will, when axially projected, lie in concentric circles centered at the cutter axis, the purpose of which will be explained a little later.

The cutter, in the particular arrangement shown, has the axially extending tapered passageway or bore 17 whose larger end is at the top. A tapered driving spindle 18 is adapted to be inserted in the bore 17 for frictionally driving the cutter. The spindle has at its lower end a stem 19 adapted to extend into or through the guide for the valve stem. The upper end of the spindle is made hemispherical, as indicated at 20 and is provided with radial projections 21.

When the cutter is to be used, the driving spindle is applied thereto and the resulting tool is engaged with the valve seat to be refaced, the stem 18 extending into the guide boss 22 in which the stem of the removed valve operated. The cutter will thus be held in axial alignment during the refacing operation. The tool can be turned by hand, or otherwise. I have shown a simple device for operating the tool, namely a socket wrench 22 in which the socket 23 is somewhat larger in diameter than the upper end of the driving spindle. The bottom wall of the socket is preferably conical as indicated at 24. The wrench is provided with bayonet slots disposed to receive the projections 21 on the spindle. When the wrench is applied to the

spindle it may rock thereon without producing any side thrust, and consequently it is unnecessary for the workman to exercise extreme care to hold the wrench accurately 5 in alignment with the spindle.

As the tool is rotated, the metal surrounding the valve passageway will be cut by the cutting edges of the teeth. As the metal is cut away, the cutter will move downward 10 axially and the valve seat will shift downwardly axially and hold definitely to its predetermined angle, width and diameter. Likewise, the surface T will shift axially 15 downwardly and the flank cutting edges underneath the head 10 will cut the material above the valve seat to leave the surface U, whose angle with the valve axis will be greater than forty-five degrees in such condition as to give proper clearance. Fig. 4 20 shows the valve seat before the refacing operation somewhat widened by use and valve grinding, and Fig. 5 shows the condition after the refacing operation, the distance Y representing the distance of axial shift 25 downwardly of the valve seat from its original factory made position. When the valve is now reapplied, it will have the same contact area with the valve seat as in its original factory made condition, the surfaces T and 30 U deflecting away from the valve face to leave only the valve seat for engagement with the valve. The operation of the valve and the flow through the valve passageway will therefore not be appreciably interfered with as a 35 result of the refacing operation.

After a cutter has been used for a time, it needs to be resharpened, and such resharpening must not disturb the shape or profile of the cutting edges of the teeth, otherwise 40 the cutting dimensions would be changed. The cutters are sharpened by grinding the radial planes or cutting faces of the teeth, and as a result of such grinding the profile of the teeth or their cutting edges will be 45 shifted upwardly axially a distance, depending upon the amount of the grinding, because the linear elements of the surfaces of said cutters are helices, and the angularity or profile of the cutting edges relative to the 50 cutter axis will not be changed, nor will the diameters of the imaginary cylindrical surfaces receiving the upper and lower edges of the belt 12 be changed. The dimensions of the cutter, so far as the refacing operation 55 thereof is concerned, will not be altered in the least.

I have shown a dished grinding wheel 26 of a type commonly used for grinding and resharpening reamers and like cutters. The 60 wheel is mounted on a driving spindle 27 and is preferably of dish shape in order to present the annular grinding surface 28 which is in a plane at right angles to the grinding wheel axis and of a width sufficient to span 65 the tooth surfaces to be ground. During

grinding of a tooth the grinding surface of the grinding wheel is kept in the radial plane of the tooth cutting edge.

In Fig. 6 I have shown diagrammatically the theory upon which the tool is constructed. Consider the blank as having only a single tooth, the radial face of which lies on the vertical plane 29-29, which plane passes through the axis, the original body of the cutter has the upper cylindrical portion 10, 70 and the three conical surfaces 30-31-32 are divided off by the lines 33 and 34.

Now assume that two cuts are made to define the single cutter tooth under consideration as shown in heavy outline. 80

Next, the relieving operation is performed by cutting back the metal from the edge toward the axis. Instead of the point of the cutting tool moving in lines lying in planes parallel to the planes of lines 33, 34, it moves 85 in lines which are helices of the same pitch, but of suitably varying diameter to conform to the conical nature of the body of the cutter.

As a result the lines 33, 34 which were 90 circles, disappear and they are replaced by the helices 33^a and 34^a which, at the edge 29-29, coincide with the lines 33, 34. The teeth may therefore be said to be relieved in such a manner that the faces extending rearwardly from the cutting edges constitute bands each of which is of uniform width throughout its length and forms a helical surface concentric with the axis of rotation 95 of the cutter. 100

In like manner circular line 35 is obliterated and the helical line 35^a takes its place.

The same thing is true at the lower end with respect to line 36 which, however, becomes merged with the relief surface of the 105 tapered part 32 of the tool.

Obviously the relieving tool, instead of having only a cutting point and tracing a line, may comprise an edge and generate the 110 tapered helicoidal surfaces desired.

The resulting tooth may be accurately described as having three adjacent oblique helicoidal surfaces of different obliquity.

While I have shown the cutting edge as disposed in a plane passing through the axis and the grinding operation as merely swinging this plane about the axis, it will be apparent that the cutting edge may be a helicoid as in the case of the so-called spiral reamer. Obviously, instead of a cutting edge 115 in three sections, more or less sections at varying angles may be employed.

If desired, the lower end of the stem 19 may have therein teeth 40 that will act to clean out the bore in the guide 16 as the stem 120 is pushed through the same.

I do not intend to be limited to the details shown and described.

I claim:

A toothed cutter for refacing valve seats, 130

the face containing the cutting edges of each tooth lying in a radial plane relative to the axis of rotation of the cutter, each tooth being uniformly relieved rearwardly of its cutting edges to produce faces each of which is uniform in width throughout its length and forms a helical band concentric with the axis of rotation of the cutter, each tooth comprising an upper part and a seat-engaging part, the cutting edge of the seat-engaging part being at an angle and of a width corresponding with the angularity and width of the seat to be refaced, and the cutting edge of the upper part being inclined to the axis of rotation of the cutter at an angle greater than that of the cutting edge of the seat-engaging part.

In testimony whereof, I sign this specification.

OLIVER M. MAISCH.
